[57] CLAIM

The ornamental design of a hammer handle, as shown and described.

DESCRIPTION

FIG. 1 is a perspective view of a hammer showing my new design.

FIG. 2 is a front elevational view thereof, wherein the rear view is identical thereto;

FIG. 3 is a side elevational view thereof wherein the opposite side view is identical thereto;

The appearance of the top end of the handle forms no part of the claimed design.

The broken line portions of the drawings are for illustrative purposes only and form no part of the claimed design.
